EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY

CORD-GUIDING MECHANISM FOR BUTTONHOLE-SEWING MACHINES

Application filed January 17, 1928. Serial No. 247,284.

This invention relates to buttonhole sewing machines, more particularly of the type having stitch-forming mechanism which turns about an axis normal to the plane of the work in sewing around the eyelet-end of a buttonhole. Such stitch-forming mechanism includes a reciprocating needle supported and operated above the work, and under-thread mechanism mounted on a rotary turret which carries the usual needle-throat member customarily formed with a guiding aperture for leading a cord within the range of action of the stitch-forming devices, so that the cord will be embraced 15 within the overseam.

Due to the fact that the turret is turned about its axis in sewing around the end of the buttonhole and is reversely turned after the buttonhole is completed, to restore the 20 stitch-forming mechanism to initial position, there has been difficulty in freely guiding the cord from the supply to the needle-throat member; the cord being heretofore subjected to a variable drag and to a take-up and slack- 25 giving action due to the changing relation of the needle-throat member to the cord leading to said member.

An object of the present invention is to provide a cord-guiding mechanism which 30 maintains a fixed relation between the needle-throat member and other cord-guiding elements, so that rotation of the turret will have no effect upon the feed of the cord from the source of supply to the needle-throat member, thus eliminating a variable condition which heretofore tended to produce variations in 35 the resultant overseam at different positions around the buttonhole.

The invention comprises the provision of 40 a lead-in or introductory cord-guide which is disposed in the axis of rotation of the turret, followed by additional cord-guiding means carried by the turret. The guiding means preferably leads the cord upwardly 45 along-side the turret, out of range of the turret-mechanism, and inwardly to the cord-guiding aperture in the needle-throat member. When the turret turns in sewing around 50 the end of a buttonhole, the guiding devices sweep around with the turret and maintain

at all times a fixed distance from the latter and from the guide-tube, thus avoiding any take-up or slack-giving action upon the cord and introducing no variable friction or drag upon the cord. The introductory guide is 55 preferably in the form of a tube mounted as a bushing in a hole in the table which supports the machine; the cord supply-spool being disposed below the table.

In the accompanying drawings, Fig. 1 is a 60 front end elevation of the bed of a button-hole sewing machine embodying the invention. Fig. 2 is a plan view of the turret and cord-guide, and Fig. 3 is a section on the line 65 3-3, Fig. 1.

The invention is shown as embodied in a buttonhole sewing machine, such as disclosed in the patent to Allen, et al., No. 1,372,473, of March 22, 1921. Such a machine comprises a reciprocating and laterally vibrat- 70 ing needle 1 and a bed 2 within which is mounted for turning movements about a vertical axis, the turret 3 carrying the usual under-thread mechanism and needle-throat member 4 having the cord-guiding aperture 75 5 through which the cord is led to a position within range of the vibrating needle 1. The under-thread mechanism includes the threaded and non-threaded loopers 3^a and 3^b, respectively, operating in an arcuate path about the 80 pivot screw 3^c.

According to the present improvement there is fixed to the turret by the screw 6 an outwardly extending arm 7 to which is fixed by screws 8 the angular guide-arm 9 having a vertical portion 10 and an inwardly and upwardly inclined portion 11 extending above the path of the loopers 3^a and 3^b and terminating near the cord-guiding aperture 5 in the needle-throat member. 90

The cord 12 is introduced to the machine from the source of supply below the table 13 through the guide-tube 14 which is set in the table coaxial with the turret 3. From the guide-tube 14, the cord is led outwardly to the guide 15 and upwardly to the guide 16, thence inwardly to the guide 17 and lastly above the path of the loopers 3^a, 3^b, Fig. 1, to the cord-guiding aperture 5 in the needle-throat member. 95 100

The guide 15 comprises a roller-stud 18 journaled on a pin 19 set in the arm 10. The stud 18 is covered by a sheet-metal guard 20 having at one end an inturned lip 21 in engagement with the arm 10. The guard 20 is secured to the arm 10 by the screw 22 and retains the cord in engagement with the roller-stud 18. The guide 16 is similar in construction to the guide 15. The guide 17 comprises a shank secured by screws 23 to the arm 11; such shank being bent at its upper free end into the form of a guide-eye 24 through which the cord 12 passes to the needle-throat member.

15 In the operation of the machine, the cord-guide sweeps around the turret's axis as indicated by the dotted semi-circle in Fig. 2, maintaining a fixed relation to the turret and needle-throat member. Also, the guide 20 15 is maintained at a fixed distance from the tube 14, so that there is no take-up or slack-giving action on the cord at any time, and the cord is maintained at all times entirely out of range of the under-thread mechanism.

25 Having thus set forth the nature of the invention, what I claim herein is:—

1. In a buttonhole sewing machine, the combination with stitch-forming mechanism including an upper needle, under-thread 30 mechanism, a rotary turret carrying said under-thread mechanism, and a needle-throat member, of a cord-guide disposed below and coaxial with the turret, and cord-guiding means carried by and spaced from said turret and adapted to lead the cord from said first mentioned cord-guide upwardly alongside and externally of the turret and inwardly to said needle-throat member, said cord-guiding means maintaining the cord out 35 of range of the under-thread mechanism.

2. In a buttonhole sewing machine, the combination with stitch-forming mechanism including an upper needle, under-thread mechanism, a rotary turret carrying said under-thread mechanism, and a needle-throat member having a cord-guiding aperture, of a cord-guide disposed below and coaxial with the turret, and cord-guiding means carried by said turret and including 45 an arm spaced from and secured to said turret and having a downwardly extending portion and an inwardly and upwardly extending portion terminating adjacent the needle-throat member, and cord-guiding means adjacent the free-ends of said portions.

3. In a buttonhole sewing machine, the combination with an upper needle, under-thread mechanism including threaded and non-threaded loopers, a needle-throat member, and a rotary turret carrying said under-thread mechanism and needle-throat member, of a cord-guide disposed below and coaxial with the turret, and means carried by the 60 turret for leading the cord from said cord-guide to said needle-throat member exter-

nally of said turret and above the path of movement of said loopers.

In testimony whereof, I have signed my name to this specification.
